UNITED STATES PATENT OFFICE.

DAVID B. LINCOLN, OF AURORA, ILLINOIS.

DESIGN FOR A HOTEL-CABINET.

SPECIFICATION forming part of Design No. 27,964, dated December 7, 1897.

Application filed June 11, 1897. Serial No. 640,390. Term of patent 7 years.

To all whom it may concern:

Be it known that I, DAVID B. LINCOLN, a citizen of the United States, residing at Aurora, in the county of Kane and State of Illinois, have invented and produced a new and original Design for Hotel-Cabinets, of which the following is a specification, reference being had to the accompanying drawings, forming a part hereof, and wherein—

10 Figure 1 is a perspective view illustrating my design for a hotel-cabinet, and Fig. 2 a plan view of the same.

The cabinet is of a generally rectangular shape, both the upper and lower surfaces being essentially square; but the upper surface is of smaller dimensions than the lower surface, whereby the sides incline outward toward the lower edges of the cabinet.

In Fig. 1 I illustrate the ornamentation of the front side, and it may be said that the other three sides of the cabinet are ornamented in the same way.

At the top of each side is a strip *a*, having the conventional wave-like scrollwork *b* formed thereon, and at the bottom of each side is a similar strip *c*, having the same scroll-work *d* thereon inverted with respect to that on the strip *a*.

At the ends of each side and constituting the edges of the cabinet are the pillars *e*, similarly ornamented. Arranged intermediate of the pillars *e* and extending vertically between the strips *a* and *c* are the narrow strips *f*, which latter are provided with the conventional ornamentation *g* thereon.

Formed upon each side of the cabinet between the strips *a*, *c*, and *f* and the end pillars *e* are the panels *A*, which are essentially rectangular in shape, preferably flat on their outer faces, and having beveled edges *h*. A very beautiful effect is obtained when these panels *A* are made of onyx or similar material, and when so made, if the strips *a*, *c*, and *f* and the pillars *e* are made of frosted silver or other dull white material, the contrast is harmonious and pleasing to the eye.

The top of the cabinet for its major part

consists of panels *B*, having beveled edges *i*, and surrounded by the continuous framing *j*, the latter being curved or rounded on its upper surface, as shown. The panels *B* are formed of a transparent substance, such as glass.

C is an elevated pedestal arranged at about the central part of the top of the cabinet, but which may be dispensed with. This pedestal when used may be ornamented as shown, having plain sides *k* and ornamented borders *l*. When used, the said pedestal is made of some dull white metal, so as to harmonize with the rest of the cabinet.

D D are circular sponge-cups let down into the top of the cabinet in front of and to each side of the pedestal *C* when the latter is used, each of said sponge-cups being preferably mounted in and surrounded by a plain square panel *m*.

E is a large receptacle directly behind the pedestal when used, and *F F* are similar receptacles on each side thereof, the latter receptacles being preferably divided into compartments by vertical partitions, as shown.

Directly in the rear of the receptacles *F F* are small rectangular openings *n*, containing bristles to serve as pen-wipers, which openings are formed in and surrounded by plain rectangular panels *o*, as shown.

G G are ink-wells of any conventional type mounted at the extreme rear corners of the cabinet, and which ink-wells may also be mounted in and surrounded by plain rectangular panels *p*, as shown.

If desired, the entire cabinet may be mounted on short legs or supports at the corners.

I claim—

A design for a hotel-cabinet substantially as shown and described.

This specification signed and witnessed this 21st day of May, 1897.

DAVID B. LINCOLN
